UNITED STATES PATENT OFFICE.

JEROME HENRY DETERS AND CHARLES KIECHLER, OF CINCINNATI, OHIO;
SAID KIECHLER ASSIGNOR TO AMOS DYE, OF SAME PLACE.

STREET-CAR SIGN.

SPECIFICATION forming part of Letters Patent No. 544,504, dated August 13, 1895.

Application filed April 22, 1895. Serial No. 546,760. (No model.)

To all whom it may concern:

Be it known that we, JEROME HENRY DETERS and CHARLES KIECHLER, citizens of the United States, residing at Cincinnati, in the county of Hamilton and State of Ohio, have invented certain new and useful Improvements in Street-Car Signs, of which the following is a specification.

Our invention relates to illuminated revolvable or changeable route-indicators or signs for the tops of street-cars and the like, the novel features of which are fully hereinafter described, and particularly pointed out in the claims.

In the accompanying drawings, Figure 1 is a longitudinal front elevation of our invention, showing the supporting car-roof in cross-section; Fig. 2, a central longitudinal section showing the supporting-standards or bracket-bearings broken off and the said car-roof omitted; Fig. 3, a longitudinal elevation of the back or inner face of one of the sign-slides; Fig. 4, an end elevation to the right of Fig. 1; and Fig. 5 a full-size cross-section of one corner of the skeleton-frame, showing two slides therein and a broken off inner elevation of the adjacent end head, the whole being taken on the dotted line $x-x'$ of Fig. 1.

A represents the ordinary car-roof, at either end or side of which the sign is mounted.

B B are the upright bracket-arms or standards, having open jaws $b-b'$ at their upper ends, and with their bases suitably secured upon said car-roof.

Our sign-frame is preferably composed of four hollow longitudinal corner-bars a, a', a^2 , and a^3 , and square end heads or flanged plates C C', the corners of the latter fitting within the several right-angled inner portions c of said corner-bars, to which they are suitably secured. Said corner-bars are each made of sheet metal, which is bent with an outer curve or arc and the said inner right angle, suitable guideways or grooves c' being constructed at the opposite ends of said arc and right-angled portion, all as best shown in Fig. 5.

D D' D² D³ represent four rectangular slides fitting within the guideways c' of our skeleton-frame, and $d-d'$ are hollow, central bearings or trunnions projecting laterally from the

end heads C C' and resting in the open jaws b of the standards B to support the sign. The trunnion d is made cylindrical and the other trunnion d' square in cross-section, whereby the sign may be released at end d' and free to turn on the other trunnion, said square trunnion d' preventing its turning when set in position for view. The slides are each composed of a stenciled sheet-metal front side or face 1 and a backing 2 of glass or other transparent material, said metal sides overlapping the glass backing in the manner best seen in Fig. 3.

The letters of the destination word ("Avondale," for instance, as in Fig. 1) are cut in the metal face, and the glass backing is of the regulation color (yellow here in Cincinnati) to correspond to that of the route over which the car is passing, thus causing said letters to most clearly appear in the desired color of the route, the solid-metal portion of the face surrounding them being, of course, perfectly opaque and giving greater intensity to said letters for the better view of the observer or waiting passenger.

E E' represent central rods or shafts projecting inwardly a short distance from the end heads C C' and connected, as well as strengthened or reinforced, by an elbowed rod F, as best seen in Fig. 2. These rods are all preferably made of ordinary gas-piping; those E E' projecting outwardly through the end heads and their hollow trunnions and constructed with a screw-thread for receiving the securing-nuts e and e' .

G and G' are incandescent electric lamps mounted in the couplings f at the inner ends of said shaft-rods E E', and g g are the current-conductors passed through said gas-pipe shafts to the lamps.

H H' are scalloped or cruciform plates having square central orifices to fit, respectively, over the trunnions d and d' , the trunnion d being made square at its inner end to properly accommodate plate H and both plates lying contiguous to the outer faces of the end heads and the ends of the said sign-slides, whereby the latter are prevented from accidental longitudinal displacement.

The elbowed rod F is preferably arranged at an inclination rearwardly, so that it shall

lie in line with one of the angles or corners of the sign, thus preventing any shadow therefrom to fall upon the front face to obscure the letters.

5 Instead of using all four sides of the sign as transparent destination-indicators, two of them (D^2 and D^3) could be supplied with mirror or reflector slide-fillings, as best seen in the heavy black line 3, Fig. 5, which represents the mirror-plating or reflecting silver backing, thus securing a better and more powerful light from the lamps to illuminate the stenciled letters in the exposed front slide and enable their clear observation at a greater distance than could be possible without such reflector-surfaces. One lamp would be ample with said reflector-backing, and in that case it should be centrally mounted in the sign.

15 In the sign shown the lamps and central shaft turn with the slide-box when one end (that to the right) has been raised from its bearing-jaw; but it is obvious that the said shaft could be made stationary and the slide-box revolve thereon by simply making the 20 trunnions fast to the outer ends of the shaft- rods (instead of to the end heads, as aforesaid,) and leaving the nuts on said shafts somewhat free from contact with the inner faces of the end heads and outer ends of the said trunnions, and also providing suitable catch devices to hold the sign in proper position for view when once set.

25 A sign with stenciled slides and either colored or no fillings, such as herein shown and described, is obviously effective for both day and night use and imparts to the passenger waiting ahead for the car a ready and definite view, both of the destination or direction of travel and the route to which the car belongs.

30 In the operation of the sign the side desired to be brought to view may be readily accomplished by simply raising or releasing the right trunnion end from its open bearing-jaw, then turning it on the left cylindrical trunnion till the destination-slide is to the front, and then replacing said right trunnion end into its bearing-jaw. To remove the slides from either end for repairs or replacing with other slides or colored fillings, the sign is re-

50 moved from its bearings, and then either one of the barrier-plates H H' is removed, thereby permitting the ready withdrawal lengthwise of either slide from place in the grooved ways. Should the sign be made with a stationary shaft, then we would prefer to mount reflectors of any suitable construction directly thereon to the rear of the lamp or lamps, so that all four faces of the sign would be clear for night use.

55 We claim—

1. In a street car sign, the combination, with two standards, one of which is provided with a square socket, of a frame journaled therein, provided with a shaft at each end, a hollow trunnion upon each shaft, one of which is 60 square and the end of the other one is square, removable slides in the sides of the frame, a scalloped baffle plate at each end of the frame having a square hole and fitting between the ends of the frame and the standards, and a 65 nut upon the outer end of each shaft for holding the trunnions against the end of the frame, substantially as set forth.

2. In a revoluble or changeable route sign or indicator for street-cars, the combination 70 of an open skeleton-frame having guide-ways therein and suitably trunnioned end-heads; one or more sign-slides composed of stenciled metallic front-faces and fillings of colored glass or other similar, suitable transparent material, and adapted to engage said guide-ways; an elbowed central-shaft made of tubing and on which said frame and its sign slide or slides are mounted; one or more 75 incandescent electric-lamps mounted on said shaft and adapted to diffuse light through the colored glass and stenciled letters of said sign slide or slides; barrier-plates or catches adjacent the outer ends of said sign slide or slides; and suitable bearing-standards for 80 the resting of the trunnions of said frame, substantially as herein set forth.

85 JEROME HENRY DETERS.
CHARLES KIECHLER.
